UNITED STATES PATENT OFFICE.

RICHARD M. POPHAM, OF MERION, PENNSYLVANIA.

BOOK FOR INCOME-TAX RETURNS.

1,285,367.

Specification of Letters Patent. Patented Nov. 19, 1918.

Application filed April 10, 1914. Serial No. 830,880.

To all whom it may concern:

Be it known that I, RICHARD M. POPHAM, a citizen of the United States, residing at Merion, county of Montgomery, State of Pennsylvania, have invented a new and useful Book for Income-Tax Returns, of which the following is a specification.

The object of my present invention is to devise a novel method of making out an income tax return, in accordance with the Government form 1040, or other similar forms, and to devise a novel book or journal therefor, whereby a yearly itemized account of individual income and deductions, necessary to make a correct and intelligent return in gross amounts to the United States Government at the end of the year, is provided.

It further consists of a novel construction and arrangement of a book or journal having a desired number of leaves for the purpose of keeping an itemized record of yearly income and general deductions, and a novel arrangement of a recapitulation sheet having symbols thereon to indicate the proper columns in which the totals are to be indicated.

It further consists of other novel features of construction and arrangement, all as will be hereinafter more clearly set forth.

For the purpose of illustrating my invention, I have shown herein, one form thereof, by means of which my invention can be accurately carried out in practice, although, as is apparent, the various instrumentalities of which my invention consists can be variously arranged and organized and my invention is not limited to the precise arrangement and organization of these instrumentalities, as herein set forth.

Figure 1 represents, in perspective, a book embodying my invention.

Fig. 2 represents a plan view of the key sheet.

Figs. 3 to 11, inclusive, represent plan views of different pages of the book conforming to different lines of the income portion of form 1040.

Figs. 12 to 17, inclusive, represent plan views of pages of the book, for reception of items conforming to the general deductions of form 1040.

Fig. 18 represents a plan view, on an enlarged scale, of the recapitulation sheet.

Similar numerals of reference indicate corresponding parts in the figures.

Referring to the drawings:

My novel book may have the different sheets thereof bound together, but it is preferably constructed as illustrated, in the form of a loose leaf book, so that any desired number of sheets may be added, as required.

The arrangement of the United States income tax return form 1040, for the use of individuals in making their annual tax returns, is by a series of lines and items. Each of these lines or items, on page two of said form, specifically describes the character of the income upon which a return is to be made. The lines from one to eight inclusive are opposite to two ruled columns adapted to have indicated therein the dollars and cents, and marked, respectively, A and B, designating whether the normal tax upon the particular income has had the tax deducted at the source, or otherwise. A separate column is shown for the total of the two columns A and B, in which this total is to be entered.

Line eleven of page two of said form 1040, relates specifically to dividends of corporations, who paid the income tax direct upon the net earnings, and all dividends upon this class of investments must be entered in the column opposite line eleven.

The Government provides for certain general deductions, on page three of this form 1040, and these are embraced in the lines one to six inclusive. Opposite to each line, the particular deductions allowed are to be placed.

The several amounts are entered in the dollars and cents columns, placed opposite to the lines, and a total of the columns is made and entered in its designated place, line seven.

Page one of United States form 1040 is devoted to the assembling of the gross income, as set forth on page two of the form, and the total of general deductions, as set forth on page three. The respective lines, and dollars and cents columns show where the respective amounts are to be placed in order to arrive at the net income. On page one of the Government form are also shown special deductions and exemptions which the Government allows. Into the dollars

and cents columns, designated with their specific line number, I enter the totals of line eleven, page two, relating to dividends, in the total, column A, page two, and lastly 5 the amount of Government exemption, three or four thousand dollars, as the case may be. The totals of these items are extended to a column, especially provided, for allowing for the deduction of the amount from the 10 net income, in order to arrive at the amount of taxable income, on which the normal tax of 1% is to be calculated.

As the Government form 1040 for individuals is intended solely for receiving the 15 gross amount of the yearly income and general deductions, the detail amounts necessary to show the yearly gross amounts must be kept in some sort of a book or memorandum form in order to intelligently arrive at 20 the correct figures on the completion of the year, and the object of my present invention is to provide for the accurate keeping of such statistics. It is often the case that 25 too much of the detail is left to the memory of the individual and hence confusion and often times errors occur. In order to minimize and reduce the matter to absolute accuracy, a series of sheets or pages, carrying the correct line and page complying absolutely 30 with all the provision of said form, is adopted, in accordance with my invention, thus giving ample room by the use of one or more sheets carrying the line and page, corresponding to United States form 1040, 35 to have entered in detail thereon all transactions of income and general deductions that may occur during the year. All the sheets relating to income and general deductions, are, together with a recapitulation 40 sheet, bound together in loose leaf or other book form.

With the above in view, 1 designates a book, or journal, embodying my invention, the pages of which are secured in assembled 45 position, by means of fastening devices 2, of any desired type. In the front part of the book is placed one or more key sheets, 3, (see Fig. 2), which conform to pages two and three of United States form 1040. Following the key is a sheet 4 having indicated thereon, a heading showing that such sheet complies with line one, page two, of the U. S. income form 1040. Then, in order, come the sheets 5, 6, 7, 8, 9, 10, 11 and 12, 50 having a heading indicating the proper line and page of the form to which they conform. After the sheets, on which the income is to be entered, follow the sheets 13, 14, 15, 16, 17 and 18, having a heading 55 thereon, indicating the general deductions and the line and page of the income form with which they comply.

Having determined from the key, the character of the income received at any particular period, the same is entered on the 60

sheet carrying the proper line and page of U. S. form 1040, and the amount is placed in the "A" or "B" column, depending upon whether the tax has been withheld at the source, or otherwise. All income received 70 from dividends and so forth will be placed on sheet 12, Fig. 11, of the book. This procedure applies likewise to items of general deductions. Each is to be entered on the sheet bearing the proper line and page, as 75 shown in the key. At the close of the year, a total footing is to be made of all the pages upon which entries appear. This having been accurately determined, the next procedure is to post or enter the totals, on the 80 recapitulation sheet under the different lines and headings called for. The next step is to add up the columns A and B of the income, setting down in the proper places the aggregate of the A and B columns. By adding in the amount of dividends, shown in line 11 of the form, to the aggregate of A and B columns, the total gross income is arrived at. The columns of 85 general deductions are now added, which 90 determine the total general deductions classified. The next procedure is to transfer to that part of the recapitulation representing page one of 1040, the total of general income to the proper space designated 95 by the star symbol $\star$. The next transfer is from the total of general deductions to the proper space designated by the triangle Δ . Deducting then one amount from the other gives the net income. Under the head 100 of special deductions and exemptions allowed by the Government, I enter the total of dividends and so forth, shown by the dividend symbol $\bigcirc$. The total of column A is to be entered on the space shown by the 105 tax withheld symbol $\square$. The gross exemption of either three or four thousand must be determined by the individual maker of the return. The grand total of these 110 three items is to be entered in the appropriate column and deducted from the net income. This will determine the amount of income liable for the normal tax of 1%.

The calculation of the sur tax, if any, can be computed and entered in the proper 115 spaces provided on the recapitulation sheet. The addition of the sur tax and the normal tax will give the amount due the Government. The regular Government return in accordance with form 1040 can be made up from 120 the recapitulation and it sets forth all the different matter called for by the form. The recapitulation sheet provides columns or spaces for indicating the "Total additional or super tax", the "Total normal tax", and the 125 "Total tax liability".

For purposes of illustration, I have preferred to show my invention as applying to the United States Government income tax form 1040, but, it will, of course, be ap- 130

parent that it is also adapted to be employed in conjunction with the income tax return form 1041, with slight modifications, and it is also adapted to be employed for other returns, all of which, it will be understood, is within the spirit and scope of my present invention. It will also be apparent that changes may be made in the arrangement of the different sheets without departing from the spirit of the invention.

It will now be apparent that I have devised a novel and useful book for income tax returns, which embodies the features of advantage enumerated as desirable in the statement of the invention and the above description, and while I have, in the present instance, shown and described a preferred embodiment thereof which will give in practice satisfactory and reliable results, it is to

be understood that the same is susceptible of modification in various particulars without departing from the spirit or scope of the invention or sacrificing any of its advantages.

Having thus described my invention, what I claim as new and desire to secure by Letters Patent, is:—

A book for Government income tax returns, comprising a series of sheets, each indicative of a line or item and page of the Government income tax return form, a key sheet indicative of the position of the gross items, and a recapitulation sheet indicative of the totals on said series of sheets.
